UNITED STATES PATENT OFFICE.

MARTIN MANNION, OF PERTH AMBOY, NEW JERSEY, AND ROBERT C. ARTHUR, OF TOTTENVILLE, NEW YORK, ASSIGNEES OF ONE-THIRD TO JOHN MANNION, OF PERTH AMBOY, NEW JERSEY.

ADJUSTABLE PLUG FOR CLEANING CONDENSER TUBES.

1,415,600.

Specification of Letters Patent.

Patented May 9, 1922.

Application filed July 1, 1921. Serial No. 431,942.

To all whom it may concern:

Be it known that we, MARTIN MANNION and ROBERT C. ARTHUR, citizens of the United States, residing at 295 Neville 5 Street, Perth Amboy, county of Middlesex, in the State of New Jersey, and Tottenville, Staten Island, in the county of Richmond and State of New York, respectively, have invented certain new and useful Improvements in Adjustable Plugs for Cleaning Condenser Tubes, of which the following is a specification.

This invention relates to improvements in means or what may be termed plugs for 15 cleaning interiorly tubes of surface-condensers, or the interior of any type of tubular appliances or devices.

The invention has for its object, among other purposes, to provide for obviating 20 the disadvantages of cleaning especially condenser tubes particularly of the type indicated, or otherwise, heretofore experienced in doing this with the use of long-handled brushes, or other ill-contrived appliances 25 therefor.

A further object of the invention is to provide for carrying out the above indicated purposes in a simple, effective and inexpensive manner and with facility, and 30 to provide for the expeditious functioning of the plug or device.

Other objects of the invention, together with the foregoing, will be apparent from the following description of the construction, operation or application and arrangement thereof, and the annexed illustration of the same.

The invention therefore consists of certain instrumentalities and features of construction substantially as hereinafter more 40 fully disclosed and defined by the appended claims.

The accompanying drawing or illustration discloses the preferred embodiment, or one 45 form, of our invention wherein it will be understood that various changes and modifications as relate to the detailed construction and arrangement of parts may be made without departing from the scope 50 thereof as covered by the claims, and in which drawing—

Figure 1 is a plan view of our surface-condenser tube cleaner.

Figure 2 is a transverse vertical section of the same.

As characteristic features of our invention we provide what may be termed preferably a plug 7, which is preferably of rubber and which in general outline is preferably that shown, consisting of a preferably central cylindrical portion 2, terminating at its ends into longitudinally tapered or approximately truncated cone-shaped extensions 3, and these in turn terminating at their smaller ends into annular, or disk-like portions which may be termed flanges 4. The flanges or disks 4 are of slightly greater diameter than the central cylindric portion 2 as diagrammatically and otherwise indicated in the drawing. These

flanges or disks are thus adapted, by being of a greater diameter than the cylindric portion 2 and, of course, than the other portions of the plug, for previous engagement when under air-compression or other pressure with the interior surface of the condenser-tube, said flanges, it will be understood, being adapted to snugly or closely

fit within the tube as the plug is initially introduced into the latter. The cylindric 80 portion 2 of the plug is provided with a plurality of grooves or passages 5 extending generally in the direction of the axis of the plug, also in preferably approximately spiral lines along the perimetric surface of 85 said cylindric portions as shown. It is observed that the plug may be also formed of an inter-mixture of rubber and some suitable abrasive material in its entirety or otherwise if found requisite for the more 90 effective functioning of the plug, as where it may have contact with hard "scale" or substances adhering to the condenser tube.

In using the plug, it is inserted into the condenser-tube or other tubular object for 95 cleaning at one end thereof and subjected to, and driven by compressed-air-pressure, or water or other pressure which may be readily locally obtained and applied to the plug in any suitable way. In case any impediment should be present in the tube, the developed pressure will be delivered to and collapse one of the flanges 4, toward the center of the plug, whence pressure will be conducted into, and be delivered by the 100 105 grooves or passages 5 toward and cause the

collapsing oppositely of the other flange or disk which will accordingly result in clearance of the plug and aid its passage, over the impediment, out through the tube.

5 From the foregoing it is believed that the purposes and advantages of our invention as set forth above have been made clearly apparent and appreciable.

Having described our invention, what we 10 claim and desire to secure by Letters Patent is:

1. A tube-cleaner of plug shape, and consisting of a projectile having an intermediate grooved portion and annular end flange-forming portions.

2. A tube-cleaner of elastic material consisting of a projectile and having an intermediate grooved portion and annular end flange-forming portions.

20 3. A tube-cleaner unit having an intermediate grooved portion and annular end flange-forming portions of greater diameter than said intermediate grooved portion.

4. A tube-cleaner consisting of an elastic 25 projectile having end flanges, and an intermediate portion adapted to function with said end flanges said flanges adapted to collapse in opposite directions under air compression or pressure to provide clearance for the plug or cleaner in case of its passage being otherwise impeded through the condenser or other tube.

5. A tube-cleaner consisting of a projectile plug of elastic material having end-flange-forming annular portions and an intermediate cylindric portion, said flange-forming portions being of somewhat greater diameter than the intermediate cylindric portion. 35

6. A tube cleaner consisting of a projectile plug of elastic material having end annular flange-forming portions, and a central or intermediate cylindric portion provided with perimetric grooves of approximately spiral lines, said intermediate cylindric portion and flange-forming portions 45 being connected by longitudinal tapering portions.

7. A tube-cleaner consisting of an elastic projectile plug having a grooved intermediate cylindric portion provided with end 50 flanges forming annular portions of greater diameter than said intermediate portion.

8. A projectile plug for flue-cleaners, consisting of a body-portion having longitudinally extending spiral peripheral grooves 55 and tapering ends and laterally extending flanges on said ends, said body and flanges being of collapsible material and said flanges extending beyond said body portion.

In testimony whereof we affix our signatures.

MARTIN MANNION.
ROBERT C. ARTHUR.
